DES. 2041

George D. Bragwell, of New York, N.Y.
Letter's Patent No. 2041, Dated April 4, 1865.
Design for Glass Case.

The schedule referred to in this Letter's Patent and making part of the same.

To all whom it may concern;

Be it known that I, George D. Bragwell, of the City, County and State of New York, have invented or produced a new and ornamental Design for Glass Case; and I do hereby declare that the following is a full, clear and exact description thereof, which will enable others skilled in the art to fully understand and make use of the same, reference being had to the accompanying drawing forming part of this specification, in which

Fig. 1. represents a top view of the upper front rail and parts of the upper side rails of a show case, made after my Design.

Fig. 2. is a front view of the base, the upper front rail, and of the upper front rail, and of the upright bars B.

Capital letters of reference indicate like parts.

This invention consists in the ornamental mouldings of the base A, a cross section of which is shown in red outline; of the upper front and side rails C and D, a cross section of which is also shown in red outline; and of the upright bars B, a cross section of which is also shown in red outline.

I claim as my and desire to secure by Letter's Patent
The Design above described for the rails of a show case.

Witness,

Mr. W. Livingston
Mr. G. G. Topliss

George D. Bragwell
